Patented Nov. 30, 1920.

INVENTOR: Rowland C. Hill

BY Rowland L. Roberts,
ATTORNEY.

UNITED STATES PATENT OFFICE.

ROWLAND C. HILL, OF FITCHBURG, MASSACHUSETTS, ASSIGNOR TO SIMONDS MANUFACTURING COMPANY, OF FITCHBURG, MASSACHUSETTS, A CORPORATION OF MASSACHUSETTS.

TOOL-HANDLE.

1,360,991.

Specification of Letters Patent. Patented Nov. 30, 1920.

Application filed May 11, 1920. Serial No. 380,585.

To all whom it may concern:

Be it known that I, ROWLAND C. HILL, a citizen of the United States of America, residing at Fitchburg, in the county of 5 Worcester and Commonwealth of Massachusetts, have invented an Improvement in Tool-Handles, of which the following is a specification.

This invention relates to tool-handles, and 10 consists in means for holding tools, having a screw-threaded shank or tang, securely therein, when once properly inserted; this object is attained by employing a spiral coil 15 of wire inserted in the hand-grip portion, which wire has the number of coils per inch either greater or less, but preferably greater, than the number of threads per inch on the tool shank which is to be used therewith.

By this means when the handle and tool 20 are screwed together the angle of the helix of the coil will be increased or decreased, depending upon whether the number of threads per inch of the screw, is lesser or greater than the number of coils per inch 25 of the helix; in the former case contracting the coil and in the latter expanding it; but in either case the friction between the contacting parts will be increased and thus tend to lock them together and prevent them from 30 becoming loose, especially when the wire coil and screw-thread of the shank have become worn.

The drawing forming a part of this specification, shows a longitudinal diametrical 35 section of the hand-grip, socket, coiled wire and ferrule and a side elevation of a part of the screw-threaded shank of a tool.

Referring to the drawing by reference characters; A is the hand-grip, B the socket 40 therein, C, the coiled wire within the socket, D, the ferrule on the end of the hand-grip and E, is the screw-threaded end of a portion of the shank of a tool.

A coiled wire of ductile metal to insure 45 good electrical connection in a lightning rod, has heretofore been screwed into a threaded socket, but it was not relied upon to prevent the pulling apart of the coupling, as the ribbed end of one of the sections was 50 bent over so as to engage the interior of the

other section and thus produce sufficient friction to hold the sections together.

In the construction of the present improvement, the spiral coil serves as a screw-thread in the socket, but also as locking 55 means for holding the tool-shank in the hand-grip when they are screwed together. If the friction of the coil within the socket is not sufficient to prevent the coil from turning therein when the tang of the tool 60 is screwed in, the outer end of the coil may be bent outward beneath the ferrule, as at F, and embedded in the hand-grip member.

This improvement will be found particularly useful for the handles of hack-saw 65 frames.

I claim:

1. A tool-handle, comprising a hand-grip member with a tool socket therein, a coiled wire in the socket, the diameter of which 70 coil is normally greater than the diameter of the socket hole, and a tool for the socket, having a screw-threaded shank the threads of which are less in pitch than the angle of the helix of the wire coil, for the purpose 75 specified.

2. A tool-handle, comprising a hand-grip member, a tool-socket therein, a tool having a screw-threaded shank, a wire coil in the socket, the pitch of the coils of which is 80 greater than the pitch of the threads of the screw on the shank of the tool to be inserted therein.

3. A tool-handle, comprising a hand-grip member with a tool-socket therein, a coiled 85 wire in the socket, the diameter of which coil is normally greater than that of the socket hole and a tool for the socket having a screw-threaded shank the threads of which are different in pitch from the angle of the 90 helix of the said wire coil.

4. A tool-handle, comprising a hand-grip member having a socket in the end thereof, a coiled wire in the said socket one end of which coil is fastened to the socket, and a 95 tool-shank provided with screw-threads which have a pitch less than that of the angle of the helix of the said wire coil.

ROWLAND C. HILL.
